UNITED STATES PATENT OFFICE.

ALONZO JULIAN, OF ALLIGATOR, MISSISSIPPI.

CIGARETTE-PAPER BOOK.

1,234,037.

Specification of Letters Patent. Patented July 17, 1917.

Application filed May 17, 1916. Serial No. 98,128.

To all whom it may concern:

Be it known that I, ALONZO JULIAN, a citizen of the United States, residing at Alligator, in the county of Bolivar, State 5 of Mississippi, have invented certain new and useful Improvements in Cigarette-Paper Books; and I do hereby declare the following to be a full, clear, and exact description of the invention, such as will enable others skilled in the art to which it 10 pertains to make and use the same.

This invention relates to holders, books, or containers for paper sheets, and is adapted particularly for holding cigarette papers 15 in such manner that the same may be carried in the pocket without danger of soiling, wrinkling, or tearing the same, and so as to enable the papers to be readily withdrawn from the container one at a time, being especially adapted to hold the papers 20 in interlocked relation, so that the withdrawal of one paper from the holder will present the free end of the succeeding sheet in convenient position to be pulled from the 25 container or book when required.

The primary object of the invention is to provide a container for papers of this character and for holding the papers in the above described manner which is of simplified and improved construction, and which 30 may be constructed or assembled without the use of any securing medium such as glue, mucilage, or other adhesive.

A further object of the invention is to 35 provide a holder or book of this character and for the purposes mentioned which may be constructed of a single sheet of paper or other material capable of being readily folded, whereby the same may be cheaply 40 and with little difficulty constructed, and which will prove thoroughly efficient in the attainment of the ends for which it is designed.

With these objects in view, together with 45 others which will appear as the description proceeds, the invention resides in the novel combination and arrangement of parts, all as will be described more fully hereinafter, illustrated in the drawings and particularly 50 pointed out in the claims.

The invention will be best understood by reference to the accompanying drawings, wherein:

Figure 1, is a perspective view of a holder 55 or book embodying the invention, the same

being shown filled with papers and ready for use.

Fig. 2 is a plan view of the blank used in the manufacture of my device,

Fig. 3 is a perspective view looking at the 60 back of the device.

Fig. 4, is a sectional view taken on line 4-4 of Fig. 1.

Referring now more particularly to the drawings, 5 indicates the body portion of 65 the blank from which the holder is formed. This blank in the preferred embodiment of the invention is formed of paper, and is folded lengthwise adjacent its longitudinal edges upon the lines 6, the said folded portion constituting longitudinal flaps 7 laid upon the body 5 and having their edges spaced slightly apart in parallel relation.

When folded in the above described manner, the ends of the structure are folded backwardly onto the body 5 on the lines 8 at right-angles to the longitudinal lines 6. The receptacle thus formed is a rectangular envelop and the distance between the lines of fold 8 is substantially equal to the width of the cigarette papers to be contained in the receptacle. The backwardly folded end flaps 9 thus formed are of such length that they overlap 70 upon the back of the receptacle and one end is preferably tucked longitudinally within 75 the free end of the opposite end beneath the marginal folds to form a locked structure.

The papers to be contained within the book are of the usual cigarette length, and 80 are folded transversely on a middle line, after which they are assembled into a book or pack by inclosing a half of one paper between the halves of the adjacent paper, the order obviously being reversed as shown in 85 Fig. 4, until the pack is completed with each paper locked between the folds of the preceding one. The papers thus assembled are inserted beneath the flaps 7 with their ends 90 parallel to the edges of the flaps 7, and with the end of the top-most of the papers extending outwardly from under the adjacent retaining flap 7 through the space between the edges of the latter and overlapping the opposite flap 7. When thus arranged, the 95 longitudinal edges of the interlocked papers project beyond the flap 9 containing the same, and the opposing end flap 9 may then be folded beneath the paper containing flap 100 and with the longitudinal flap members 7 thereof engaged over the corresponding flaps 105

110

of the adjacent flap 9. When thus folded, it is seen that a pocket is formed beneath the overhanging members 7 on the face of the blank, and the interlocking of the ends of 5 the longitudinal flaps 7 carried by one of the end flaps 9 beneath the other end, holds the container securely in assembled position. As the protruding end of the outer paper is pulled, the same unfolds, in its withdrawal, 10 the fold of the next succeeding paper with which it is interlocked, and the end of the said succeeding paper is pulled or unfolded in such manner as to project through the space formed between the parallel spaced 15 edges of the longitudinal flaps 7, but in the opposite direction.

It is thus seen that a simple and efficient cigarette book is provided, and one wherein the same is readily formed or constructed 20 and held in proper assembled form without the use of mucilage or other adhesive. The simplicity of the container and the ease with which it may be constructed and assembled enables the same to be manufactured at ex- 25 tremely low cost, and with suitable inscription upon the front and back of the holder, the same could be employed as an attractive advertising medium.

While I have herein shown and described 30 a particular or preferred embodiment of the invention, I wish it to be understood that I need not confine myself to all the precise details of construction herein set forth by way of illustration as modification and va- 35 riety may be made without departing from the spirit of the invention or exceeding the scope of the claims.

What is claimed is:

1. A paper holder of the class described, 40 comprising a rectangular sheet of material folded at its longitudinal edges to provide inwardly projecting flaps, said flaps form-

ing a pocket and the edges thereof being in spaced parallel relation, the said sheet having its ends bent inwardly to overlap, 45 and one of said ends being inclosed by the flaps of the opposite end, substantially as described:

2. A paper holder of the class described, comprising a rectangular sheet folded at its 50 longitudinal edges to provide inwardly projecting flaps, said flaps forming a pocket and the edges of said flaps being in spaced parallel relation, the said sheet having its ends bent backwardly in overlapping relation, 55 the lowermost of the overlapping end flaps having its longitudinally disposed flaps engaged over the corresponding flaps of the uppermost of the end flaps, and sheets arranged in interlocked relation within said pocket and with the end of the outermost sheet projecting through the space between the spaced longitudinal flaps, substantially as described.

3. A paper holder of the class described 65 comprising a sheet of paper oblong in shape and folded inwardly along its longitudinal edges to provide longitudinal flaps, the edges of said flaps being in spaced parallel relation to each other, and the ends of the sheet 70 being bent inwardly in overlapping relation, paper sheets arranged in interlocking relation on and inclosed by the longitudinal flaps, and the longitudinal flaps of the undermost of said overlapped end flaps being 75 engaged over the corresponding flaps of the uppermost end flap, substantially as described.

In testimony whereof, I affix my signature, in the presence of two witnesses.

ALONZO JULIAN.
